US0D1031210S

(12) **United States Design Patent** (10) **Patent No.:** **US D1,031,210 S**
(45) **Date of Patent:** **** Jun. 18, 2024**

(54) **HAND SANITIZING STATION**

(71) Applicant: **Audrey Jennings**, Chicago, IL (US)

(72) Inventor: **Audrey Jean Jennings**, Chicago, IL (US)

(**) Term: **15 Years**

(21) Appl. No.: **29/723,525**

(22) Filed: **Feb. 7, 2020**

Related U.S. Application Data

(63) Continuation-in-part of application No. 16/101,989, filed on Aug. 13, 2018, now Pat. No. 10,660,983, which is a continuation of application No. 15/599,439, filed on May 18, 2017, now abandoned.

(57) **CLAIM**

The ornamental design for a hand sanitizing station, as shown and described.

DESCRIPTION

FIG. 1 is a front perspective view of a hand sanitizing station showing my new design;

FIG. 2 is a front elevation view thereof; and,

FIG. 3 is a side elevation view thereof.

The dashed broken lines in the figures represent portions of the hand sanitizing station that form no part of the claimed design.
